HALTER

William H. Crandall, Oakland, Calif.

Application August 15, 1941, Serial No. 406,969

3 Claims. (Cl. 54—24)

This invention relates to an improvement in the construction of the rope halter shown in my former Patent No. 1,939,107 entitled Halter, issued December 12, 1933 and my patent Number 2,114,178 entitled Halter, issued April 12, 1938, and particularly to the connection formed between the throat latch and nose piece of the halter.

In the construction shown in my former patent, six separate metal pieces were employed to form the connection between the nose and throat latch of the halter and these were so disposed that there was a tendency to chafe the throat of the animal to which the halter was applied.

The object of the present invention is generally to improve and simplify the construction and operation of the connection between the nose and throat latch; to materially reduce the number of parts employed and to dispose of parts in such a manner that chafing is prevented.

The invention is shown by way of illustration in the accompanying drawing, in which

Fig. 1 is a perspective view of the halter;

Fig. 2 is an enlarged perspective view of the connection formed between nose and throat latch of the halter;

Fig. 3 is a longitudinal section taken on line III—III, Fig. 2;

Fig. 4 is a detail view showing the manner in which the ends of the rope forming the nose piece are joined and laid behind the second rope forming the lower part of the nose piece;

Fig. 5 is a perspective view of a clamp; and

Fig. 6 is a perspective view of an elongated ring which is secured by the clamp.

Fig. 7 is a cross section taken on line VII—VII, Fig. 1.

Referring to the drawing in detail and particularly Fig. 1, it will be noted that a halter is formed from two pieces of rope—a short piece forming a nose piece 3 and a long piece which forms the crown, the cheeks and the throat latch of the halter. The long rope commences at the point indicated at 5 where it is secured by a pair of clamping bands 6. The rope extends downwardly as indicated at 7 and is passed through a pair of clamping bands 8 and 8a. The rope then doubles back on itself and in so doing forms a loop 9. It passes back through the clamps 8 and 8a and then extends upwardly as indicated at 10, then through an eye member 11 and here again forms a loop and doubles back on itself, and is extended forwardly to form one cheek piece 12. It extends to the nose piece 3 where it passes through a pair of clamping bands

13 down under the chin as indicated at 14 and up on the other side of the nose pieces through a pair of clamping bands 15, then rearwardly to form a second cheek piece 16. It again passes through the clamping bands 6, then upwardly over the head as indicated at 17 and down the opposite side where it is doubled back on itself to form a loop 18, which carries a snap hook or latch 19a to engage the ring 11. It again passes upwardly around the head as shown at 19 and finally through a friction buckle 20 which is secured at one end between the clamps 6.

The portions of the rope 17 and 19 which pass over the head form the crown piece of the halter. These two portions of the rope are held together by a ring 22. The ropes, however, pass loosely through it and as the free end of the rope passes through the friction buckle 20, the length of the crown piece may be adjusted to suit heads of varying sizes and lengths. The clamps 13 and 15 rigidly secure the short rope 3 forming the nose piece and a part of the chin piece to the forward ends of the cheek pieces 12 and 16. The free ends of the short rope 3 meet centrally under the chin as indicated at 21, see Fig. 4, and are secured together by a metallic clamping sleeve 23. The sleeve 23 securing the free ends of the nose portion 3 lies parallel with the portion 14 and both are secured within a clamp 24. The lower portion of this clamp also serves to secure a flattened ring 25, the purpose of which will hereinafter be described. That is—the sleeve 23, shown in Fig. 4, temporarily secures the free ends of the nose piece 3, but they are permanently secured when the clamp 24 is applied as this tends to clamp the sleeve 23 against the rope 14. The clamp 24 tending to further compress the sleeve 23 to positively secure the free rope ends.

The elongated ring 25 is disposed on the lower side or beneath the clamp 24. Extending through it is a pair of leg members 26 which are looped at one end to form a ring 27, these legs are looped again at the opposite ends to form an eye 28 through which the loop of the throat latch extends. The eye 28 thus forms a connection between the forward end of the throat latch and the leg members or shank 26 which extends through the flattened ring 25 at a point beneath the clamp 24 and terminates in the ring 27 to which a halter rope, not shown, may be attached. A smooth surface, to wit—the upper face of the clamp 24 and the shank 26 is thus presented to the underside of the chin or throat of the animal to which the halter is applied and

no chafing will take place. Also, it should be noted that the flattened ring 25 has an offset or deepened portion 29 which limits lateral movement of the shank and halter ring 27 with relation to the clamp 24, thus further reducing any tendency to chafing.

The halter ring 27, the eye 28 and the shank or leg members 26 are formed from heavy round wire and as such forms a strong connection to which a halter rope may be attached. The opposite end connects with the throat latch and this in turn is connected to the crown through the rope section 7 and 9 and the cheek pieces 12 and 16 so that when a pull is exerted on the halter it will be transmitted directly to the whole head of the animal and will thus cause the halter to grip and hold snugly.

It was previously stated that the crown piece consisting of the rope sections 17 and 19 were adjustable to increase or decrease the length of the halter so as to fit heads of different sizes or lengths. The throat latch is similarly adjustable, that is: The clamp 8 is permanently attached but the clamp 8a may be slid along the rope and the throat latch may thus be shortened or lengthened. The clamp 8a is made of two halves secured together by a screw, hence, when the clamp has been adjusted it will be secured by tightening the screw.

In actual use the halter is applied by unsnapping the latch 11a. The nose piece 3 is slipped over the nose of the animal and the crown piece is thrown over the head behind the ears; the latch is then snapped into the ring 11 and the operation of applying the halter is completed. Conversely, when removing the halter, it is only necessary to release latch 11a and to slip the halter off. Hence, the halter can be quickly applied or removed.

A halter constructed as shown has great strength and is exceedingly durable. The only portion subject to wear of any extent is the shank 26 which passes through the elongated ring 25, but as the shank is made of two sections of heavy round wire and the flattened ring 25 is similarly made, any danger from breakage by wear is virtually eliminated; further, it should be noted that only three pieces are required to form the connection between the nose piece and the throat latch, to wit: the clamp, the elongated flattened ring and the shank member extending therethrough, the sleeve 23 may or may not be used but is preferable as it retains the loose ends of the nose rope 3 in place when the clamp 24 is applied and thus simplifies assembly and while this and other features of my inven-

tion have been more or less specifically described and illustrated, I nevertheless wish it understood that changes may be resorted to within the scope of the appended claims, and that the materials and finish of the various parts employed may be varied according to what the experience of the manufacturer and varying conditions of use may demand.

Having thus described my invention, what I claim and desire to secure by Letters Patent is:

1. In a halter of the character described, a piece of rope adapted to encircle an animal's nose and having ends meeting beneath the chin; a clamp securing the rope ends together; a second piece of rope forming cheek pieces and a

throat latch and having a portion disposed alongside the clamp which secures the meeting ends of the first piece; a second clamp surrounding the first named clamp and the second rope and securing them together; a flattened ring carried by said second clamp and disposed beneath said second named clamp and ropes, said throat latch terminating in a loop; a ring having a shank portion extending through the flattened ring and an eye on the other end of the shank through which the loop of the throat latch extends.

2. In a halter of the character described, a nose piece having a lower portion comprised of two parallel contacting ropes; an elongated

clamp surrounding the ropes and securing them together; a flattened ring carried by the clamp and disposed beneath the clamp and the ropes; a shank member extending through the flattened ring, said shank having an eye at one end and a ring at the opposite end and said eye and ring being disposed at right angles to each other and a throat latch having a loop at its end and said loop extending through the eye of the shank.

3. In a halter of the character described, a nose piece having a lower portion comprised of two parallel contacting ropes; an elongated

clamp surrounding the ropes and securing them together; a flattened ring carried by the clamp and disposed beneath the clamp and the ropes; a shank member extending through the flattened ring, said shank having an eye at one end and a ring at the opposite end and said eye and ring being disposed at right angles to each other and a throat latch having a loop at its end and said loop extending through the eye of the shank.

4. In a halter of the character described, a nose piece having a lower portion comprised of two parallel contacting ropes; an elongated clamp surrounding the ropes and securing them together; a flattened ring carried by the clamp and disposed beneath the clamp and the ropes; a shank member extending through the flattened ring, said shank having an eye at one end and a ring at the opposite end and said eye and ring being disposed at right angles to each other and a throat latch having a loop at its end and said loop extending through the eye of the shank, and a depressed portion in the flattened ring to

50 permit the shank to pass through and to limit lateral movement of the shank within the flattened ring.

WILLIAM H. CRANDALL.
